[57] **CLAIM**

The ornamental design for a bottle crate, as shown and described.

DESCRIPTION

FIG. 1 is a top perspective view of a bottle crate in accordance with my new design;

FIG. 2 is a bottom perspective view of the bottle crate of FIG. 1;

FIG. 3 is a side elevational view of the bottle crate of FIG. 1, the opposite side being a mirror image thereof;

FIG. 4 is an end elevational view of the bottle crate of FIG. 1, the opposite end being a mirror image thereof;

FIG. 5 is a top plan view of the bottle crate of FIG. 1;

FIG. 6 is a bottom plan view of the bottle crate of FIG. 1;

FIG. 7 is a side elevational view of the bottle crate of FIG. 1 with a broken line showing of bottles loaded thereon;

FIG. 8 is a cross-sectional view of the bottle crate taken generally along line 8—8 of FIG. 5;

FIG. 9 is a cross-sectional view of the bottle crate taken generally along line 9—9 of FIG. 5;

FIG. 10 is a cross-sectional view of the bottle crate taken generally along line 10—10 of FIG. 5;

FIG. 11 is a cross-sectional view of the bottle crate taken generally along line 11—11 of FIG. 5; and,

FIG. 12 is a cross-sectional view of the bottle crate taken generally along line 12—12 of FIG. 5.

The broken line showing of bottles in FIG. 7 is for illustration purposes only, and forms no part of the claimed design.
